UNITED STATES PATENT OFFICE.

JAMES BALLANTYNE HANNAY, OF LOCH LONG, SCOTLAND.

APPARATUS FOR MANUFACTURING WHITE PIGMENT.

SPECIFICATION forming part of Letters Patent No. 729,493, dated May 26, 1903.

Original application filed August 30, 1901, Serial No. 73,871. Divided and this application filed October 10, 1902.
Serial No. 126,799. (No model.)*To all whom it may concern:*

Be it known that I, JAMES BALLANTYNE HANNAY, a subject of the King of Great Britain and Ireland, residing at Cove Castle, Loch

- 5 Long, in the county of Dumbarton, Scotland, have invented certain new and useful Improvements in Apparatus for Manufacturing White Pigment, (for which I have made application for Letters Patent in Germany, No. H. 27,103, dated November 29, 1901; in Germany, No. H. 27,641, dated February 28, 1902; in Germany, dated August 21, 1902; in France, No. 316,708, dated December 9, 1901; in Belgium, No. 160,480, dated December 21, 1901; 15 in Austria, dated January 20, 1902; in Italy, No. 43, Vol. 152, dated March 31, 1902; in Sweden, No. 116/02, dated January 21, 1902; in Norway, No. 14,732, dated January 24, 1902; in Hungary, No. 24,438, dated January 25, 1902; 20 in Luxemburg, No. 4,672, dated January 22, 1902; in Switzerland, No. 28,604, dated January 27, 1902; in Russia, No. 16,215, dated January 15/28, 1902; in Spain, No. 29,189, dated June 6, 1902; in Turkey, No. 999, dated January 30, 1902; in Canada, No. 98,597, dated February 8, 1902; in Victoria, No. 19,005, dated February 26, 1902; in New South Wales, No. 11,809, dated February 27, 1902; in Portugal, No. 3,900, dated June 23, 1902, and in Great 25 Britain, No. 2,297, dated February 1, 1901,) of which the following is a specification.

My invention relates to apparatus used in the manufacture of white pigment of basic sulfate of lead from galena or other sulfid-of-lead ore by furnacing operations.

35 My invention consists in improvements in furnaces suitable for the oxidation of lead sulfid to lead sulfate.

Referring to the accompanying drawings, 40 Figure 1 is a sectional elevation of my improved furnace. Fig. 2 is a plan of the same.

In carrying my invention into effect I construct a cylindrical furnace *a* with a basic-lined cylindrical interior *b*. Preferably I use 45 the common magnesia and lime basic material, as employed in the basic-steel process. I line the furnace with this basic material made into suitable bricks or by ramming it around a central core. On the plate-iron bot-

50 tom *c* of the furnace is placed a layer of coke breeze *d* and a pile of the coke slabs *e*. Three twyers *f* enter the furnace at about twenty

inches below the top surface of the coke *e*, which is built up to the level of an air-inlet *g*, other air-inlets, *h*, being provided farther 55 up the furnace.

A conveyer or other device *m* feeds the galena down a vertical passage *k*, opening into an inclined pipe *j*, in which is a suitably curved and inclined platen for distributing the galena 60 evenly over the coke. At the top of the furnace is a chimney *o*, fitted with a damper *p* for use when starting the furnace. An exit *i* for the fume, also fitted with a damper *q*, connects the furnace with a dust-box *r*, through 65 which the fume is drawn on its way to the condensing and collecting apparatus.

From the top of the dust-box *r* a valve-controlled branch pipe 101 leads to a fan and condenser, which is common to a number of furnaces and is used to draw discolored fume 70 when accidentally produced.

Having now described my invention, what I claim as new, and desire to secure by Letters Patent, is—

75 1. A furnace for the production of white sulfate - of - lead pigment consisting of a hearth, coke slabs piled on the same, a furnace-body with a basic lining, air-inlets for both forced and induced draft, together with means 80 for feeding granular galena into the furnace.

2. A furnace for the production of white sulfate - of - lead pigment consisting of a hearth formed by a layer of coke breeze on a metal plate, a furnace-body with a basic lining, air-inlets for both forced and induced 85 draft, together with means for feeding granular galena into the furnace.

3. A furnace for the production of white sulfate - of - lead pigment consisting of a 90 hearth formed by a layer of coke breeze on a metal plate, a furnace-body with a basic lining, air-inlets for both forced and induced draft, together with a conveyer which feeds granular galena onto an inclined plate contained in an inclined feeding-pipe leading into 95 the furnace.

In witness whereof I have hereunto set my hand in presence of two witnesses.

JAMES BALLANTYNE HANNAY.
